CLAIM

The ornamental design for a display screen or portion thereof with animated graphical user interface for quantitative documentation to assist in running code strategy, as shown and described.

DESCRIPTION

FIG. 1 is a front view of a display screen or portion thereof with animated graphical user interface for quantitative documentation to assist in running code strategy showing a first image in the sequence showing the present design; FIG. 2 is a second image thereof; FIG. 3 is a third image thereof; FIG. 4 is a fourth image thereof; FIG. 5 is a fifth image thereof; FIG. 6 is a sixth image thereof; and, FIG. 7 is a seventh image thereof.

The long dash-short dash lines indicate the boundary of the display screen and form no part of the claimed design. The short dash-short dash lines and broken text illustrate text areas, text, or graphical features that form no part of the claimed design.

The appearance of the animated images transitions between the images shown in FIGS. 1-7. The process or period in which one image transitions to another forms no part of the claimed design.
